UNITED STATES PATENT OFFICE.

FRED J. MILLER, OF PITTSBURGH, PENNSYLVANIA.

LOCKING-RECEPTACLE.

1,356,301.

Specification of Letters Patent. Patented Oct. 19, 1920.

Application filed November 6, 1919. Serial No. 336,067.

To all whom it may concern:

Be it known that I, FRED J. MILLER, a citizen of the United States, residing at Pittsburgh, in the county of Allegheny and State 5 of Pennsylvania, have invented certain new and useful Improvements in Locking-Receptacles, of which the following is a specification.

This invention relates to locking receptacles, designed primarily for the reception of milk bottles, although it is to be understood that it can be employed for any purpose wherein it is found applicable, and the invention has for its object to provide a receptacle of such type, in a manner as hereinafter set forth, with means operated by the bottle closure or cap thereof, when the bottle is placed within the receptacle for locking the lid of the latter closed to prevent surreptitious removal of the bottle from the receptacle.

With the foregoing and other objects in view the invention consists of the novel construction, combination and arrangement of parts as hereinafter more fully described, and illustrated in the accompanying drawings, wherein is shown an embodiment of the invention but it is to be understood that changes, variations and modifications can 30 be resorted to which come within the scope of the claims hereunto appended.

In the drawings wherein like reference characters denote corresponding parts throughout the several views:—

35 Figure 1 is an elevation of a locking receptacle in accordance with this invention the lid thereof being swung back.

Fig. 2 is a vertical sectional view of the receptacle closed and showing a milk bottle 40 mounted therein.

Fig. 3 is an enlarged vertical sectional view of the upper portion of the receptacle, the latter being closed.

The receptacle comprises a base 1, a hollow body portion 2 and a lid or cover 3, which is hinged to the top of the body portion 2, as at 4. The body portion 2 provides a chamber 5, in which is adapted to be mounted the bottle 6, or any other article, 50 to be housed or safe guarded.

The walls or wall of the chamber 5 are lined with non-conducting or impervious material 7, and the height of the chamber 5 is such that it will extend above the top of the bottle 6, the latter having a closure or cap 8.

The lid 3 is provided with an opening 9, and also with a small casing 10, which is secured therewith and depends from the lower face thereof. The bottom of the casing has 60 an opening 11, and operating through the latter, so as to abut against the cap 8, is a spring controlled plunger 12, having its lower end formed with a head 13.

The plunger 12 is carried on the lower end 65 of a curved spring 14 which extends up through the opening 9 and into a locking bolt casing 15, which is secured upon the outer face of the lid 2. Arranged within the casing 10, is a flat spring 16, having 70 its forward end secured to the plunger 12 and its rear end fixed with the casing 10 and lid 3, so that when the bolt 17, in the casing 15, is released the spring 15 will cause the lid 3 to spring open. The springs 14 and 75 16 provide a suspension means for the plunger 12.

The bolt 17 is formed with a pocket 18 and a slot 19 in casing 15, and extended into the pocket 18, is the upper end of the spring 80 14, and the said upper end of the spring 14 is connected to the bolt 17, by a pin 20, the latter slides within the slot 19, and under construction the spring 14 is connected to the bolt 17 by a pin and slot connection. 85

Secured to the body portion 2, is a keeper, which is formed of a vertically disposed casing 21, having an opening 22 for the entrance of the bolt 17. The keeper projects above the top edge of the body portion 2, 90 and the opening 22 is in the path of movement of the bolt 17. The keeper has a key hole opening 23 in the side thereof, and is also formed with a key guide 24 for a key so that the latter when turned can force the 95 bolt 17 rearwardly to release the lid, the pin and slot connection providing for this movement of the bolt.

The casing 15 is inclosed by a strip 25, which projects beyond the lid 3 and overlaps the keeper. The extension of the strip 100 25 provides a finger piece or grip 26 so that the lid 3 can be lifted conveniently.

From the foregoing arrangement and construction of parts the bolt 17 will be shifted 105 into the keeper when the plunger comes in contact with the cap in the bottle mouth, the cap acting as an abutment for the plunger which will force the spring 14 upwardly and forwardly thereby shifting the bolt into the 110 keeper and locking the lid. When the bolt is shifted rearwardly clear of the keeper the

spring 16, as well as the spring 14, will act to spring open the lid.

What I claim is:—

1. A receptacle for the purpose set forth comprising a body portion, a bolt-keeper secured therewith and having an opening adapted to be arranged in the path of a bolt, a lid pivoted to the body portion and provided with an opening, a plunger positioned below said opening, a key released locking bolt carried by the lid and adapted to engage in the keeper for locking the lid, a curved spring slidably connected to the locking bolt and extending through said opening and connected to the plunger and adapted to cause the shifting of the bolt to locking position when the plunger engages an article within the body portion, and a flat spring connected to the plunger and to the lid.
2. A receptacle for the purpose set forth comprising a body portion, a bolt keeper secured therewith, a lid hinged to the body portion, a locking bolt arranged on the lid and capable of being shifted to engage in the keeper to lock the lid to the body portion, a plunger below the lid and operated

by the abutment thereof against an article within the body portion, a curved spring slidably connected at its upper end to the bolt and its lower end to upper end of the plunger and extended down through the lid, and a spring arranged wholly below the lid connected therewith and to the plunger, said springs providing a suspension means for the plunger.

3. A receptacle for the purpose set forth comprising a body portion, a lid hinged thereto, a bolt keeper carried by the body portion, said lid having an opening, a curved spring extended down through said opening, a bolt on the lid and having a pin and slot connection with the upper end of said spring, a casing on the lid inclosing said bolt, a plunger secured at its upper end to the lower end of the spring, a flat spring positioned below the lid and connected therewith and to the plunger, a casing depending from the lid and inclosing said last mentioned spring and through the bottom of which said plunger extends, and a casing inclosing the bolt.

In testimony whereof I affix my signature.
FRED J. MILLER.
